UNITED STATES PATENT OFFICE.

EDWARD J. BRAUER, OF UNIVERSITY CITY, MISSOURI, ASSIGNOR TO BRAUER BROS.
MFG. CO., OF ST. LOUIS, MISSOURI, A CORPORATION OF MISSOURI.

GOLF BAG.

Application filed December 1, 1924. Serial No. 753,289.

This invention pertains to golf bags.

The ordinary golf bag is usually constructed of fabric or other suitable material and in order to stiffen the same so that it will 5 keep its shape, such a bag is often provided with metal stays running longitudinally thereof so as to support the body in extended form. These stays are usually applied by inserting the same in pockets running 10 lengthwise of the bag, these pockets being formed by stitching or otherwise securing to the body of the bag a strip of fabric or leather or other suitable material. In the handling of such a bag, a favorite position for 15 carrying the same is under the arm with the arm encircling the upper part of the bag. Such handling usually causes wear locally at that end of the bag and since the stays form the stiffest portion of the body, the 20 greater part of the wear takes place at the leather strips covering the stays.

It is one of the objects of this invention to provide suitable protective means to these stay strips to take up the wear and prevent 25 tearing of the stitching of the stay pockets so as to open said pockets and expose the stays.

Further objects will appear from the following description taken in connection with 30 the accompanying drawing, in which:—

Figure 1 is a view in elevation illustrating a golf bag embodying this invention;

Figure 2 is a section on line 2—2 of Figure 1; and

Figure 3 is an enlarged detail section on line 3—3 of Figure 1.

Referring now to the drawing, 1 designates the body of the bag which may be constructed of fabric or other suitable material and is provided with re-inforcing rings 2 and 3 at the bottom and top thereof and a similar ring 4 near the middle thereof. The body is reinforced by metallic stays 5 confined in pockets formed by stitching to the body strips 6 of leather, fabric, or other suitable material. The stays 5 may be fastened to the rings 2, 3, and 4 by means of rivets 7 or other suitable fasteners. The stays 5, together with the rings 2, 3, and 4 to which they are attached form a semi-rigid framework for the bag. In the bag illustrated, the handle 8 is secured to a strip 9 which in turn is secured to the rings 3 and 4 and further braced by a metallic cross 55 piece 10 secured to a pair of stays 5.

In accordance with this invention, the stays 5 including their covering strips 6 are protected between the rings 3 and 4 by a metallic covering or shield 11. This shield 11 may be constructed of aluminum or other suitable metal and in the case illustrated, is made of channel form having inturned edges 12. The strips 6 are stitched to the body in such a way as to leave a margin 13 beyond the line of stitching. In applying the 60 shields 11, the inturned edges 12 are crimped under the margins 13 of the strips 6. The shield 11 may be carried under the rings 3 and 4 and secured thereto by including them in the grip of the rivet 7.

It will be seen that the shields 11 completely cover the strips 6 forming the pockets for the stays 5. Since these shields extend along that portion of the bag body which receives most of the wear of handling, it will be 65 evident that the shields will take the wear and protect the covering strips 6, thus the useful life of the bag may be greatly extended.

It is obvious that various changes may be 80 made in the details of construction without departing from the spirit of this invention; it is, therefore, to be understood that this invention is not limited to the specific details 85 shown and described.

Having thus described the invention, what is claimed is:

1. A golf bag, comprising, an elongated body, a stay supporting said body, and a metallic covering for said stay.

2. A golf bag, comprising an elongated body, a stay supporting said body, a covering for said stay, and a metallic guard for said covering.

3. A golf bag, comprising, an elongated body, a stay supporting said body, a covering for said stay stitched to said body, and a metallic shield for said covering.

4. A golf bag, comprising, an elongated body, a stay supporting said body, a covering for said stay stitched to said body so as to leave a margin, and a metallic shield for said covering secured to said margin.

5. A golf bag, comprising, an elongated body, a stay supporting said body, a covering for said stay stitched to said body so as to leave a margin, and a metallic shield for said covering crimped over said margin.

6. A golf bag, comprising, an elongated body, a stay supporting said body, a cover 110

for said stay, and a metallic shield for said cover marginally secured thereto.

7. In a golf bag having an elongated body, and stays supporting said body, the combination with a reinforcing framework mounted thereon and positioned by said stays.

8. In a golf bag having an elongated body, stays supporting said body, and a covering for said stays, the combination with a reinforcing framework externally mounted on said body and secured to said stay coverings.

9. In a golf bag having an elongated body

and stays supporting said body, the combination with a reinforcing framework 15 mounted on said stays and encircling said body.

10. In a golf bag having an elongated body, stays supporting said body, and a covering for said stays, the combination with 20 a reinforcing framework externally mounted on said body and secured to said stay coverings, and encircling said body.

In testimony whereof I affix my signature this 3rd day of October, 1924.

EDWARD J. BRAUER.
